UNITED STATES PATENT OFFICE.

JAMES DEWAR, OF CHICAGO, ILLINOIS.

CINDER-NOTCH STOPPER.

Application filed February 19, 1927. Serial No. 169,498.

My invention relates to a cinder notch stopper for blast furnaces and has particular reference to a power operated cinder notch stopper by means of which the cinder notch is opened to allow the slag to flow out of the furnace, and also by means of which the stopper is inserted in the cinder notch opening without the necessity of inserting the stopper by hand or guiding it into position by hand, as has been the practice heretofore.

Another and further object of my invention is the provision of a cinder notch stopper which is positive in its operation and which swings upward and backward away from the cinder notch opening out of the path of the heated slag, sparks, hot gases and the like which escape through the opening, and which can be easily and quickly inserted and which is just as positive in its operation as far as the insertion of the plug in the cinder notch is concerned, as it is in the opening, thus enabling the operator to quickly close the cinder notch stopper preventing the escape of gas or the molten slag.

I am aware that power notch stoppers have been in use before, but their construction has been of such a character that they are not positive enough in their operation or quick enough in their application to positively cut off the flow of slag through the cinder notch opening should it occur, or else they bind in the monkey during the removal and insertion of the stopper. In the early operation of blast furnaces these cinder notches were closed by a stopper mounted on the end of a dolly bar and when it was desired to open the cinder notch the end of the dolly bar was struck with a sledge, loosening the plug and the plug was then withdrawn by a workman. The opening of the cinder notch was a simple operation but the closing of the notch was not so simple and was also very dangerous because the sparks, molten slag, hot gases and the like, being forced out through the cinder notch opening rendered the closing operation exceedingly dangerous. Also, it was difficult to locate the exact position of the opening for the insertion of the plug and the dolly bar, often resulting in the loss of metal and taking the blast off the furnace.

In my improved apparatus I provide a dolly bar having a fixed guide at the rear end thereof, the upper end of which engages a track which guides the dolly bar directly into the cinder notch opening in a substantial horizontal position when it is desired to close the opening after allowing the escape of the slag and cinder from the furnace.

These and other objects of my invention will be more fully and better understood by reference to the accompanying sheet of drawings, in which:

The figure is a side elevational view of my improved invention.

Referring now specifically to the drawing, a blast furnace wall 10 is shown having a cinder notch 11 therein which is closed by a large frusto-conical shaped cooler 12 and a smaller cooler 13 inserted in the end of the large cooler 12, with a small cooler or cinder notch monkey 14 inserted in the cooler 12, the cinder notch monkey having an opening therethrough adapted to be closed by a hollow plug 15 mounted upon and in screw-threaded engagement with a pipe 15^a, which in turn is secured to a dolly bar 16, the dolly bar 16, the pipe 15^a and the plug 15 all being in horizontal alignment with each other. The dolly 16 is supported intermediate its ends by one leg 17 of an A-lever pivotally mounted at 18 upon a frame member 19, the other member 20 of the A-lever having a link 21 secured thereto which is connected to a cylinder 22 by a piston 23 which operates in the cylinder 22. The upper end of the cylinder 22 has a pipe 23^a connected thereto and the lower end thereof has a pipe 24 connected to said cylinder by means of which steam, compressed air, or other fluid may be admitted to and exhausted from the cylinder 22 by means of manually operable valves, located in the pipes 23^a and 24 at a point remote from the blast furnace and out of the way of any possible danger from the cinder flowing out of the cinder notch opening. A counterweight 25 is provided which is secured to the lever arm 20 by a cable 26 which assists in the opening of the cinder notch stopper and also acts as a counterbalance against the weight of the dolly bar in the closing operation.

At the rear end of the dolly bar 16 is a guide lever 27, the lower end of this lever be-

ing bent into alignment with the dolly bar 16 and secured thereto by a pair of rivets 28, so there is no relative movement between the arm 27 and the dolly bar 16, this guide 5 lever being in effect a continuation of the dolly bar 16. The upper end of the lever 27 has a link 29 secured thereto in the end of which a roller 30 is mounted which is adapted to engage upon a guide member 31 secured 10 to the member 19 in any suitable manner, as by a pair of bolts or rivets 32. The lower end of the guide member 31 is slightly angularly disposed and extends backward and upward for a short distance and 15 then is sharply curved upward for a considerable distance so that in the initial movement backward of the dolly bar on the opening of the cinder notch and for a distance of approximately two feet the dolly 20 bar is moved substantially horizontal and thereafter the rear end of the dolly bar is caused to travel upwardly and in a somewhat circular direction in order to quickly draw the plug 15 out of the path of the cinder. When it is desired to insert the plug 25 15 in the cinder notch stopper, the reverse operation takes place, with the rear end of the dolly bar being dropped more rapidly than the forward end passes forward, the 30 result being that the dolly bar is very quickly placed in a horizontal position preparatory to entering the cinder notch, this form 35 of the guide member 31 enabling the dolly bar to be quickly drawn out of the path of the molten cinder and because of its particular shape making the positive insertion of the plug into the cinder notch and easy and quick operation. The dolly bar 16 at the outer end thereof has an enlarged head 33 40 thereon which is adapted to receive the blows from the sledge to loosen the plug 15 should the stopper become frozen in the monkey 14.

A trough 34 is provided having an upper portion 35 and a lower portion 36, the trough 34 having a pipe 37 connected to the bottom thereof which is secured to a second pipe 38 by means of a swinging joint 39, this pipe in turn leading to the pipe 15^a and is 45 connected to a smaller pipe running longitudinally inside of the pipe 15^a by means of which a cooling fluid such as water is conveyed to the plug 15, this water being forced through the plug 15 and returning through 50 the pipe 15^a which is connected to an outlet pipe 40 which is connected to a second pipe 55 41 by a swinging joint 42, this construction being the ordinary common construction employed for the purpose of cooling cinder 60 notch stoppers.

The operation of the device is exceedingly simple in that when it is desired to open the monkey 14, pressure is admitted in the lower end of the cylinder 22 through the pipe 24 65 which exerts a force in a backward direction

upon the dolly bar 16 and pulls the plug 15 out of the monkey 14 in a horizontal direction. As the dolly bar travels backward it is raised a slight distance because of the travel of the A-lever and also by the elevation of the rear end of the dolly bar running on the track or guide 31. When the plug 15 is approximately two feet away 70 from the cinder notch opening the curved portion of the guide carries the outer end of the dolly bar upward and at the same time it travels outward so the dolly bar and plug are moved away from and out of the path of the molten slag and hot gases escaping through the cinder notch opening. When it 75 is desired to close the cinder notch opening the operator exhausts the pressure in the lower end of the cylinder and admits pressure to the upper end thereof, forcing the cylinder down and raising the counterweight 80 25 and forcing the stopper 15 into the opening in the monkey 14 very quickly, due to the short distance which the monkey is positioned away from the cinder notch opening 85 and also to the curvature of the track 31 90 which allows the rear end of the dolly bar to drop very quickly, placing the device in a horizontal position so that it readily enters the opening in the monkey 14 thus effectively and quickly closing the cinder 95 notch opening.

While I have described more or less precisely the details of construction, I do not wish to be understood as limiting myself thereto, as I contemplate changes in form 100 and the proportion of parts and the substitution of equivalents as circumstances may suggest or render expedient without departing from the spirit or scope of my invention.

I claim:

1. A cinder notch stopper comprising in combination, a dolly bar, a stopper mounted on one end thereof, an operating lever connected to said dolly bar intermediate the ends thereof, power operating means connected to said lever, a guide connected to the rear end of said dolly bar, and a track extending backward and upward upon which the upper end of the said guide is adapted to travel.

2. A cinder notch stopper comprising in combination, a dolly bar, a stopper mounted on one end thereof, an operating lever connected to said dolly bar intermediate the ends thereof, power operating means connected to said lever, a guide lever connected to said dolly bar towards the rear end thereof, a track upon which the upper end of the said guide is adapted to travel, and guiding means on the upper end of the said lever, the said track extending backward and upward for a part of its length and thence being curved upward.

3. A cinder notch stopper comprising in combination, a dolly bar, a stopper mounted

on one end thereof, an operating lever connected to said dolly bar intermediate the ends thereof, power operating means connected to said lever, a guide lever connected to said dolly bar towards the rear end thereof, a track upon which the upper end of the said guide is adapted to travel, and guiding

means on the upper end of the said lever, the said track extending backward in a substantial horizontal position for a part of 10 its length and thence being curved upward.

Signed at Chicago, Illinois, this 15th day of February, 1927.

JAMES DEWAR.
